CIGARETTE MAKING MACHINE

Samuel Krasnow and William Edelberg, Montreal,
Quebec, Canada; said Edelberg assignor to said
Krasnow

Application October 23, 1940, Serial No. 362,432

1 Claim. (Cl. 131—65)

This invention relates to improvements in cigarette making machines, and particularly to those machines which are operated by hand.

An object of the invention is to provide a simple, compact and durable machine that will produce cigarettes of the desired size and length.

Other objects will be set forth hereinafter.

The device consists briefly in means to feed tobacco to a strip of paper carried by an endless belt through a shaper or former, to form a cigarette tube by overlapping the edges of the strip over the tobacco charge and crimping them together, and to cut off the tube in suitable lengths. The device is operated by a hand crank.

Reference is made to the accompanying drawings in which:

Figure 1 is a perspective view of the device.

Figure 2 is a longitudinal section through the line 2—2 of Figure 1.

Figure 3 is a perspective view of the insert.

Figure 4 is a section on the line 4—4 of Figure 3.

Figure 5 is a perspective view of the trough cover.

Figure 6 is a cross section of Figure 1 on the line 6—6.

Figure 7 is a cross section of Figure 1 on the line 7—7.

Figure 8 is a cross section of Figure 1 on the line 8—8.

Figure 9 is a cross section of Figure 1 on the line 9—9.

Figure 10 is a cross section of Figure 1 on the line 10—10.

Figure 11 is a view of the cutting mechanism.

Figure 12 is a back view of the cutting wheel.

Referring to Fig. 1, the vertical supporting wall 1 is supported on a suitable base, such as a table. Pins 10 and 11 journal pulleys 20, 21 of an endless belt 2. A pin 12 journals the paper roll 13. A pin 14 journals a gear wheel 25 and crimping wheel 44. A pin 15 journals the gear wheel 24. A portion of the upper part of the wall 1 is cut away and has brackets 16 to support a feeding tray 17. An end plate 18 is secured to the base. The end of the wall has a slot 19 to permit the entrance of gear 51, to mesh with gear 23. The belt 2 is driven by a gear wheel 23 secured to the pulley 21 on the pin 11. Meshing with the gear wheel 23 is a gear wheel 24 on the pin 15. A pin 26 from the wall 1 supports a hand crank 28 with a toothed end meshing with gear wheels 24 and 25. The belt 2 has a tension device 22. In the drawing this is shown as actuated by a spring.

The trough 3 is supported at one end on the pin 30 and towards the other end by the bracket 31, mounted adjustably on the wall 1. The front part of the trough 3 is open. It starts flat at the end where the belt 2 and strip of paper from the roll 13 enter. As it advances it becomes bowed downwardly and narrowed, as shown in cross sections Figs. 6 and 7. The sides of the trough 3 in this portion have inturned lips, an inner lip 32 to direct the belt 2 and an outer lip 33 to direct the strip of paper. The rear part of the trough 3 continues the bowed semi-circular form which gradually diminishes in the diameter as shown in cross sections, Figs. 8, 9 and 10. The sides 34 of this portion of the trough 3 extend laterally and then are bent inwardly to receive the lateral edges of the cover 35 which is arched and gradually diminished in diameter to correspond with the trough 3. Transparent material is used for the cover. The cover 35 has a notch 36 and a slot 37.

Secured within the cover 35 is the insert guide 4, which starts as a full arched semicircle and gradually narrows to its slotted end 40 in the sides of which slot is journaled a minute burr wheel 41. The wider portion of the guide 4 has secured to its surface a spacer plate 42 which narrows rearwardly. By this means a passage for the edges of the belt 2 and the paper is provided between the cover 35 and the insert 4, as shown in Fig. 8. The insert 4 is bent upwardly towards its end 40. A minute baffle 43 extends under the burr wheel 41, to protect the wheel from the tobacco as it passes.

Mounted on the pin 14 and integral with the gear wheel 25 is the crimping wheel 44 which bears on the burr wheel 41 through the overlapping edges of the paper which it crimps together.

The cutter mechanism is as follows: A bracket 5 secured to the outside of the wall 1 by the pin 11 supports a pin 50 on which are journaled a gear wheel 51 which meshes at right angles with the gear wheel 23 and a cutter wheel 6.

The gear wheel 51 has a pin 52 projecting from both sides. On the outer side the pin 52 travels in a circular slot 60 in the wheel 6, beyond which it is connected to a pin 61 near the edge of the wheel 6 by a spring 62. A removable cutting blade 63 is secured tangentially to the wheel 6. The edge of the wheel 6 is cut away as shown to provide a stop 64.

Journaled on the bracket 5 at its outer end 55 is a cam 53 held under tension by the spring

54 to meet the pin 52 on the inside of the gear wheel 51. The cam 53 has a projecting tooth 55 which bears on the edge of the wheel 6 and enters the stop 64 where it remains until the cam 53 is moved outwardly by the pin 52 and releases the wheel 6.

A bracket 7 secured to the base carries a short tube 70 to receive the cigarette tube from the belt 2. The end plate 18 has a similar short tube 18¹ mounted to provide a narrow opening through which the blade 63 passes to cut off the cigarette tube.

With a construction such as above set forth, or its equivalent, the operation is as follows:

The strip of paper from the roll 13 is fed over the belt 2 into the trough 3 and below the outer lips 33. The belt 2 carries the paper past the tray 17 from which the tobacco is fed into the trough 3 in a suitable amount. The paper bearing its charge of tobacco then passes under the insert 4, as shown in Fig. 8, the edges of the paper being gradually brought together and then overlapping, one edge being lowered by a notch 36 in the cover 35. The tobacco is now below the insert 4, the overlapping paper passing above the insert and between the burr wheel 41 on the end of the insert 4, and the crimping wheel 44 operating through the slot 37 in the cover 35. The tobacco passes under the baffle 43 free from the burr wheel 41. As the formed cigarette leaves the cover 35 and the insert 4 it provides a continuous tube which is carried by the belt 2 and through the tubes 70 and 18¹. The blades 63 operating under tension cuts the cigarette tube in the proper lengths and the operation is completed.

The operation of the cutter mechanism is as follows:

The gear wheel 51 is rotated by the gear wheel 23. As it rotates the pin 52 in the slot 60 held by the spring 62 and pin 61 rotates the wheel 6. When the tooth 54 of the cam 53 enters the stop 64 it holds the wheel 6 from rotation and the pin 52 travels in the slot 60 and extends the spring 62. As the cam 53 meets the pin 52 on the gear wheel 51 the tooth 54 is moved out of the stop 64 and the wheel 6 is released and due to the tension of the spring 62 the wheel 6 snaps round rapidly. The blade 63 passing between the tubes

70 and 18¹ makes a clear cut of the cigarette tube.

An important feature of this device is the transparent cover 35 over the forming portion of the trough 3. It is slidably mounted in the overlapping edges 34 of the trough 3 and can be readily removed. By means of this cover 35 the forming operation can be observed and any defect in the forming operation detected and readily corrected.

By means of the adjustable bracket 31 the pressure between the crimping wheel 44 and the burr wheel 41 can be regulated.

It is to be noted that due to the shape of the insert the tobacco is maintained in cylindrical form and the cigarette produced is not flattened as in many cigarette machines which employ a grooved roller on the tobacco before the paper overlaps the charge.

It is to be further noted that due to the mounting of the feeding, forming and driving mechanism on one side of a vertical wall, all these parts are open and readily available to the control and observation of the operator.

What we claim is:

In a cigarette machine the combination of a vertical wall, an endless belt mounted on pins in the wall, a trough supporting the upper layer of the belt, a feed portion of the trough open above, a horizontal tray mounted on the wall, its edge overlapping one edge of the trough, a forming portion of the trough having an arched cover secured to the sides of the trough, an arched insert secured to one end of the cover and spaced apart therefrom, a burr wheel journaled in the narrowed far end of the insert, a crimping wheel bearing on the burr wheel through a slot in the cover, gear wheels journaled on pins in the wall adapted to rotate the crimping wheel and drive the belt, a hand crank meshing with the gear wheels, means for supporting a roll of paper mounted to feed a strip of paper on the belt, and means for cutting said paper periodically, the insert having an upward bend towards the burr wheel end adapted to provide spring tension to the burr wheel against the crimping wheel.
